UNITED STATES PATENT OFFICE.

ERNST MECKBACH, OF VOHWINKEL, NEAR ELBERFELD, GERMANY, ASSIGNOR TO
FARBENFABRIKEN VORM. FRIEDR. BAYER & CO., OF ELBERFELD, GERMANY, A
CORPORATION OF GERMANY.

DECALCOMANIA MATERIAL.

1,070,713.

Specification of Letters Patent. Patented Aug. 19, 1913.

No Drawing.

Application filed March 22, 1910. Serial No. 550,852.

To all whom it may concern:

Be it known that I, ERNST MECKBACH, doctor of philosophy, chemist, citizen of the German Empire, residing at Vohwinkel, 5 near Elberfeld, Germany, have invented new and useful Improvements in Decalcomania Materials, of which the following is a specification.

In the practice of decalcomania or the ornamentation of wood, glass, porcelain, stone- 10 ware, etc., by transferring pictures from a carrier of paper and other substances to the materials to be decorated, the picture or design is formed of pigment or pigments held 15 in a body or layer of a special binder mounted on such paper or other substance. Upon application to the surface of the material to be ornamented and moistening, the layer carrying the design loosens from the carrier and adheres to such surface. The 20 binder must of course be of such nature that upon moistening with water it will not disintegrate or allow the design to change in shape while at the same time it must develop 25 adhesion to the new surface and loosen its adhesion to the old. And upon redrying after transfer it must become hard and solid. In the prior art, the colors have been employed in connection with a binder of water- 30 soluble mucilaginous substances, such as gum arabic, gum tragacanth, dextrin, etc. The presence of these gummy materials invariably caused the cracking and the subsequent 35 scaling away of the transferred picture in drying. I have now found that, if in mixing the colors and producing the designs upon the carrier for decalcomania or transfer pictures, I employ as binders the salts of high-molecular aliphatic acids which 40 are contained in saponifiable materials, especially in oils, fats, waxes and resins, such as oleic acid, stearic acid, abietic acid, etc., I am able to make materials for decalcomania from which designs can be transferred 45 as layers in the manner familiar in the prior art and which do not crack or peel off from the decorated material as has been the case heretofore.

In order to illustrate my invention, the following example is given, the parts being by weight:—10 parts of colophonium are dissolved with five parts of sodium carbonate in 40 parts of water, 80 parts of barytes

white ($BaSO_4$) are mixed with this mass which is then dyed with 3 parts of fast 55 brown. This composition is then applied to a carrier, usually of a textile or fibrous nature, such as paper to produce the desired design or pattern. Such a carrier is of course insoluble in water and can thus be 60 stripped bodily from the colored design after the decalcomania material has been applied to the article to be decorated and moistened in the usual way. Instead of alkaline salts of the resin acids of colophonium, salts of the acids of copals, or waxes, 65 or stearic acid, etc. may be used.

What I claim is:—

1. In decalcomania materials, a carrier of textile material having supported thereon 70 and readily detachable therefrom a layer carrying a design or pattern, such layer consisting of salts of high-molecular aliphatic acids of saponifiable matter and incorporated coloring matter, and being free of 75 water-soluble gummy or mucilaginous substances.

2. In decalcomania materials, a carrier of textile material having supported thereon 80 and readily detachable therefrom a layer carrying a design or pattern, such layer consisting of a soap of high-molecular aliphatic acids of saponifiable matter and incorporated coloring matter, and being free of 85 water-soluble gummy or mucilaginous substances.

3. In decalcomania materials, a carrier of textile material having supported thereon 90 and readily detachable therefrom a layer carrying a design or pattern, such layer consisting of a sodium soap of high-molecular aliphatic acids of saponifiable matter and incorporated coloring matter, and being free of 95 water-soluble gummy or mucilaginous substances.

4. In decalcomania materials, a carrier of water-insoluble material having supported thereon and readily detachable therefrom a layer carrying a design or pattern, such layer consisting of a soap and incorporated 100 coloring matter, and being free of water-soluble gummy or mucilaginous substances.

5. In decalcomania materials, a carrier of paper having supported thereon a layer 105 readily detachable therefrom, said layer carrying a design or pattern and consisting of

a soap with coloring matter incorporated therewith, and being free of water-soluble gummy or mucilaginous substances.

6. In decalcomania materials, a carrier of paper having supported thereon a layer readily detachable therefrom, said layer carrying a design or pattern and consisting of a soap of a high-molecular aliphatic acid having coloring matter incorporated therewith, and being free of water-soluble gummy or mucilaginous substances.

7. In decalcomania materials, a carrier of paper having supported thereon a layer readily detachable therefrom, said layer carrying a design or pattern and consisting of a sodium soap of a resin acid having coloring matter incorporated therewith, and being free of water-soluble gummy or mucilaginous substances.

20 8. In decalcomania materials, a carrier of

paper having supported thereon a layer readily detachable therefrom, said layer carrying a design or pattern and consisting of a soap resulting from the saponification of colophonium and a pigment incorporated therewith, and being free of water-soluble gummy or mucilaginous substances.

9. In decalcomania materials, a water-insoluble backing carrier layer provided with an attached design layer composed of soap and coloring matter and free of gummy, oily or hygroscopic substances.

In testimony whereof I have hereunto set my hand in the presence of two subscribing witnesses.

ERNST MECKBACH. [I. S.]
